Primary Examiner — Cathron C Brooks*Assistant Examiner* — Christian P. McLean(74) *Attorney, Agent, or Firm* — James L. Young; Westman, Champlin & Koehler P.A.(57) **CLAIM**

The ornamental design for a unitary product label, as shown and described.

DESCRIPTION

FIG. 1 is a front perspective view of a unitary product label, showing the new design;

FIG. 2 is a rear perspective view thereof;

FIG. 3 is a rear plan view thereof;

FIG. 4 is a side view thereof (from the left side of FIG. 3);

FIG. 5 is a side view thereof (from the right side of FIG. 3);

FIG. 6 is a top view thereof;

FIG. 7 is a bottom view thereof; and,

FIG. 8 is a front plan view thereof.

The broken lines in FIG. 1 illustrate the environment of the design and form no part of the claimed design.

1 Claim, 4 Drawing Sheets
